(57) CLAIM

We claim the ornamental design for a lavatory, as shown and described.

DESCRIPTION

FIG. 1 is a perspective view of a lavatory deck showing my new design;

FIG. 2 is a front elevation view thereof;

FIG. 3 is a top plan view thereof;

FIG. 4 is a left-side elevation view thereof; and,

FIG. 5 is a right-side elevation view thereof.

The ornamental design which is claimed is shown in solid lines in the drawings.

The broken lines immediately adjacent to the shaded areas represent the bounds of the claimed design while all other broken lines are for illustrative purposes only; the broken lines form no part of the claimed design.
